[57] CLAIM

The ornamental design for a tumbler, substantially as shown and described.

DESCRIPTION

FIG. 1 is a side elevational view of a tumbler showing
my new design;

FIG. 2 is a top plan view thereof; and

FIG. 3 is a bottom plan view thereof.

The design shown in FIG. 1 is repeated at 90° intervals around the circumference thereof.

Fig. 1.

Fig. 3.

Fig. 2.
